UNITED STATES PATENT OFFICE.

JOHN S. HUNTER, OF COALINGA, CALIFORNIA.

POWER-TRANSMITTING MECHANISM.

1,136,137.

Specification of Letters Patent.

Patented Apr. 20, 1915.

Application filed March 8, 1913. Serial No. 752,989.

To all whom it may concern:

Be it known that I, JOHN S. HUNTER, a citizen of the United States, residing at Coalinga, in the county of Fresno and State of California, have invented a new and useful Power-Transmitting Mechanism, of which the following is a specification.

This invention relates to power transmitting mechanism particularly designed for use in connection with well pumping machinery although it is to be understood that it can be employed wherever it is desired to convert rotary motion into reciprocating movement.

Where well pumping machines having walking beams are employed it is customary to connect one end of the beam by a pitman to a crank shaft. This construction is objectionable, however, because it not only produces an excessive amount of friction and, consequently, necessitates the expenditure of an undesirable amount of power, but also produces an undesirable pounding action which soon wears or breaks the parts.

One of the objects of the present invention is to provide improved means whereby the walking beam of a well pumping machine can be operated easily without producing an undesirable amount of friction and without causing excessive pounding by certain of the parts of the mechanism.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a side elevation of a portion of a walking beam and showing the present improvements combined therewith, the gears being shown in their intermediate position. Fig. 2 is a view similar to Fig. 1 and showing the gears in one extreme position. Fig. 3 is a view similar to Figs. 1 and 2, but showing the gears in their other extreme position. Fig. 4 is a transverse section through the beam and showing the power transmitting mechanism in elevation. Fig. 5 is a section on line A—B Fig. 1.

Referring to the figures by characters of reference C designates one end portion of a walking beam, the same being engaged by a stirrup 1 secured to and extending upwardly from a block 2. A rack bar 4 extends from the block 2 and one end portion of the rack bar is curved so as to engage a bolt 5 which extends transversely through the lower curved end of another rack bar 6. The upper end of rack bar 6 extends to the block 2 which is thus located between the two rack bars 4 and 6. Rack bar 6 is arranged oppositely to the rack bar 4 but in a different plane so that, when the two bars are viewed as in Fig. 2, a continuous opening 8 appears between them. The bolt 5 which connects the lower ends of the rack bars 4 and 6 passes through a spacing disk or washer 9 and also passes through one end portion of a guide plate 10 the greater portion of which is parallel with the bars 4 and 6. The other end of this guide plate is mounted on a bolt 11 which extends into or through the block 2. A longitudinal slot 12 is formed in the plate 10 and extends to points above and below the teeth on the respective rack bars 4 and 6.

The drive shaft used in connection with the apparatus has been indicated at 13 and is extended between the rack bars 4 and 6 and into the slot 12. That portion of the shaft located between the rack bars is provided with gears 14 and 15 mounted to rotate freely, the gear 14 being constantly in mesh with the teeth on rack bar 6 while the gear 15 is constantly in mesh with the teeth on rack bar 4. A spacing disk 16 is mounted on the shaft 13 between the gears and serves not only to hold the said gears out of contact with each other but also to hold them against displacement relative to the rack bars, this being due to the fact that the disk is sufficiently large to lap both of the rack bars as shown in Fig. 3. A collar 17 is secured to the shaft 13 adjacent gear 14 and another collar 18 is secured to the shaft adjacent gear 15. Each of the collars 17 and 18 is provided with a peripheral notch 19 each notch being directly back of the other notch. Pivotal mounted on the outer side of each gear 14 and 15 is a dog 20. An ear 21 is secured to the same side of the gear and interposed between the ear 21 and the dog 20 is a spring 22 which serves to hold the head 23 of the dog normally pressed against the periphery of the adjacent collar.

The dogs on the two gears are oppositely disposed, as shown particularly in Fig. 1.

The dogs 20 extend across the sides of the adjacent rack bars and extending from said sides are tripping pins 24 and 25, the pin 24 being arranged on the rack bar 6 while the pin 25 is arranged on the rack bar 4. Furthermore these two pins are located adjacent opposite ends respectively of the rack bars and in the structure shown the vertical distance between the two pins is substantially equal to the semi-circumference of the gears 14 and 15.

With the shaft 13 rotating in the direction indicated by the arrow in Fig. 1, it will be apparent that collar 18 will, through the wall of notch 19 and the spring pressed dogs 20, pull on the gear 15 and thus cause the rack bar 4 to move downwardly. Rack bar 6 will move downwardly with rack bar 4 and gear 14 will therefore be caused to rotate in a direction opposite to that in which gear 15 is rotating. When the rack bars 4 and 6 move downwardly to predetermined points, the pin 25 is brought against the outer end of the dog 20 on gear 15 and said dog is thus shifted against its spring 22 so as to withdraw the head 23 from the peripheral notch 19 in collar 18. Thus gear 15 becomes disconnected from shaft 13. Simultaneously with this action, the notch in collar 17 is brought into register with the head 23 on the other dog 20 and said

head promptly shifts into the notch so that further rotation of the shaft 13 will cause gear 14 to rotate therewith and thus shift the rack bars 4 and 6 upwardly. This upward movement will continue until the pin 24 is brought against the outer end of the dog 20 on gear 14 whereupon said dog will be disengaged from its collar 17 at which time the other dog 20 will spring into engagement with collar 18. Thus a back and forth movement of the rack bars is produced.

What is claimed is:—

Power transmitting mechanism including a revoluble shaft, gears loosely mounted thereon, oppositely disposed rack bars constantly meshing with the respective gears, notched collars revoluble with the shaft and adjacent the respective gears, spring pressed dogs carried by the respective gears and normally engaging the collars, and tripping means outstanding from and movable with the rack bars for successively disengaging the dogs from the collars during the rotation of the shaft.

In testimony that I claim the foregoing as my own, I have hereto affixed my signature in the presence of two witnesses.

JOHN S. HUNTER.
